UNITED STATES PATENT OFFICE

DURLIN N. VAN ALSTYNE, OF SYRACUSE, NEW YORK, ASSIGNOR OF FIFTY PER CENT
TO JAMES N. VAN ALSTYNE, OF FULTON, NEW YORK

BOTTLE CLOSURE

Application filed August 4, 1927. Serial No. 210,534.

This invention relates to a new and improved closure for milk bottles and the like. Devices of this character now known to the art are, in every instance, difficult to place on the bottle or remove therefrom, and the main object of my invention is to provide a device which can be placed on a bottle easily and quickly, and removed therefrom in like manner.

Another object is to provide a closure which can be used repeatedly. Other objects and advantages relate to the details and form of parts, all as will more fully appear from the following description taken in connection with the accompanying drawing, in which:—

Figure 1 is a top plan view.

Figure 2 is a section on line 2—2, Figure 1.
Figure 3 is a side elevation.

Figure 4 is a section similar to Figure 2 showing a modified method of forming the end of the skirt of the device.

Figures 5 and 6 are views similar to Figure 2 illustrating two different ways of operating the device.

My invention consists of the combination of a cap —1— and a sealing disk —2—. The cap —1— is preferably formed of paper sufficiently thin so that it will remain at all times easily pliable, and impregnated with paraffin or the like to make it impervious to liquid. The sealing disk —2— is circular in form and of a size to fit tightly on the shoulder —3— regularly found on the inside of the mouth of a milk bottle —4—, and is preferably made of stiff cardboard.

The cap —1— is formed into a cup shape, preferably by forming folds or plaits —5— in the sides causing the same to conform to the general shape of the top of the bottle

—4— and has the end of the skirt —6— return bent on itself to retain the folds —5— in position. This latter operation may be performed by bending back the skirt —6— on the outside thereof, as shown at —7— in Figure 2, or, by bending the skirt —6— on the inside thereof, as shown at —8— in Figure 4.

The cap —1— is of sufficiently great diameter so that when it is in position on a bottle, it is in circumferentially spaced relation to

the outside periphery and top of the bottle top —4—, as can perhaps be more easily seen in Figures 2, 4 and 5. The skirt —6— extends downwardly from the top of the bottle a distance approximately equal to the diameter of the bottle neck —9—.

In operation my device functions as follows:—

The cap —1— is placed loosely on the bottle top —4—. A disk —2— is then placed on top of cap —1— and pressed down into position on shoulder —3—. The cap —1— being easily pliable, will conform to the shape of disk —2— and shoulder —3— and will contact with disk —2— to hold the latter firmly in position. The cap and disk in sealing position are shown in Figures 2 and 4. In this position the bottle is tightly sealed against escape of liquid, and the pouring lip —10— is protected against any contamination.

When it is desired to remove the cap from the bottle, it being in spaced relation to the top of the bottle —4—, easily adapts itself to a finger-hold, as shown in Figure 5, by means of which it may be lifted off the bottle.

It is also possible, and perhaps preferable, to grasp the skirt —6— and pull the same downward. This will cause the top of the cap to rise and lift the disk —2— from its seat on shoulder —3—, after which the cap may be lifted from the bottle. The construction and operation of the device is such that it may be used again and again without injury, for it is not necessary to use a knife or other means to break the seal, as is usually the case with devices of this character, nor is there any liability of spilling any of the contents of the bottle when the cap is being removed.

Altho I have shown and described a specific structure as illustrating an embodiment of my invention, I do not desire to restrict myself to the exact form, shape or arrangement of parts, as various changes may be made within the scope of the appended claim.

I claim:

In a bottle closure, a pliable member loosely encircling the bottle top and normally in spaced relation thereto, and having a depending skirt extending downwardly along the

bottle neck and being free to move vertically in relation thereto in both directions, and a sealing disk superposed on said pliable member and coacting therewith to seal the mouth of the bottle.

5 In witness whereof I have hereunto set my hand this 28th day of July, 1927.

DURLIN N. VAN ALSTYNE.
